UNITED STATES PATENT OFFICE

SAMUEL J. SMYTH, OF HAWTHORNE, CALIFORNIA

CLOSURE CAP

Application filed July 5, 1927. Serial No. 203,489.

My invention relates to closure caps for containers, such as milk bottles, cheese boxes, or any form of container where the caps are formed of paper, cardboard or other material.

5 It is a purpose of my invention to provide a closure cap of the above described character which eliminates the employment of any instrument in removing the cap from the container by the provision of projections 10 on the cap adapted to be gripped by the hand and actuated to flex the cap to a released position with respect to the mouth of the container.

15 I will describe only one form of closure cap embodying my invention, and will then point out the novel features thereof in claims.

In the accompanying drawings:

Fig. 1 is a view showing in edge elevation one form of closure cap embodying my invention in applied position to a milk bottle.

Fig. 2 is a view showing the closure cap in top plan and in applied position to a milk bottle.

Fig. 3 is a vertical, sectional view taken on the line 3—3 of Fig. 2.

Fig. 4 is a view similar to Fig. 3 showing the cap in released position.

Fig. 5 is a vertical, sectional view taken on the line 5—5 of Fig. 3.

30 Similar reference characters refer to similar parts in each of the several views.

Referring specifically to the drawings, my invention, in its present embodiment, comprises a disk-shaped body 15 of cardboard or any other suitable material capable of being manually flexed, and of such diameter as to have a locking fit within the mouth 16 of a bottle or other container, and to thereby seal the contents of the bottle. As shown in 35 Figs. 2 and 3, the disk body is constructed to provide ribs 17 projecting upwardly from the surface of the body. In the present instance I have shown the cap provided with two such ribs spaced apart in parallelism and 40 relatively long. These ribs are constructed to provide a gripping means by which the disk body can be flexed upwardly to cause its edges to be released from the container mouth so that the subsequent removal of the 45 cap from the bottle can be readily effected.

In practice the cap is removed from the bottle mouth by placing the thumb and finger against the outer sides of the ribs 17 and pressing until the edges of the cap at the sides of the ribs rise from the sides of the bottle mouth when the cap can be removed without danger of spilling its contents. To again seal the bottle, the cap can be replaced by pressing its edges down flat until the previous condition is attained.

A cap constructed in accordance with my invention obviously eliminates the use of an instrument to effect its removal from a container, and in removing the cap it is not distorted or otherwise impaired in respect to 65 its further use in sealing the contents of the container.

Although I have herein shown and described only one form of closure cap embodying my invention, it is to be understood that 70 various changes and modifications may be made herein without departing from the spirit of my invention and the spirit and scope of the appended claims.

What I claim is:

1. A closure cap, comprising a disk-shaped body of a material capable of being flexed and having portions thereof upstruck to provide spaced protuberances to be gripped and pressed together to cause upward flexing of 80 the edges of the body.

2. A closure cap comprising a body of flexible material adapted, when in the mouth of a container, to be engaged at its edges and retained in closing position within the 85 mouth, and spaced protuberances on the body for flexing the body to cause portions of its edges to move outwardly and thus free themselves to allow removal of the body 90 from the mouth.

SAMUEL J. SMYTH.
